UNITED STATES PATENT OFFICE.

HENRY G. CORDLEY, OF GLEN RIDGE, NEW JERSEY.

WATER-COOLER STAND.

1,015,615.

Specification of Letters Patent. Patented Jan. 23, 1912.

Application filed August 26, 1910. Serial No. 579,071.

To all whom it may concern:

Be it known that I, HENRY G. CORDLEY, a citizen of the United States, residing at Glen Ridge, in the county of Essex, State of New Jersey, have invented certain new and useful Improvements in Water-Cooler Stands, of which the following is a description, reference being had to the accompanying drawings, forming a part hereof.

10 My invention relates to stands designed especially for supporting water coolers, and the object thereof is to provide a stand which may be readily assembled, it being understood that such stands are commonly 15 shipped and stored in collapsed or knocked-down condition in order to economize in space; and to provide a stand in which the legs are securely interlocked with a ring member forming a part thereof by the act 20 of putting a brace member in place as the stand is assembled, whereby a strong and rigid stand is procured.

My improved stand is illustrated in the accompanying drawing, described in the 25 following specification, and particularly claimed in the clauses of the concluding claim.

In the drawing: Figure 1 is a view showing a section through one of the legs of a stand in which my invention is embodied, another leg being shown in elevation and the lower ends of the legs being broken away; Fig. 2 is a view showing a section taken upon a horizontal plane just above 30 the brace member of my improved stand; Fig. 3 is a view showing the manner in which the brace member and legs are secured together; Fig. 4 is a view showing the upper end of a leg of slightly modified form, 35 and a portion of the ring with which the legs are connected, and Fig. 5 is a sectional view further illustrating the form shown in Fig. 4. Fig. 6 is a sectional view illustrating a further modification of my improved stand.

In the drawings, 1 represents the legs of the stand, it being preferable to use three legs as shown in the drawing although my invention is equally applicable to a stand 50 having four or more legs. The legs are formed from bar iron segmental in cross section, the form of legs being best shown in Fig. 2.

2 is a ring supported at the upper ends of 55 the legs and designed to support a water cooler, said ring being right angular in

cross-section and arranged with a vertical portion outermost and an inwardly extending horizontal portion as shown.

Referring first to Fig. 1, the upper end 60 of each of the legs is flattened and bent at a right angle to provide an inwardly extending horizontal portion 3 adapted to lie beneath the horizontal portion of the ring 2, which horizontal portion is offset vertically 65 at 4 so that the extremity 5 of said horizontal portion may lie upon the upper surface of horizontal portion of the ring 2, said ring being provided with a slot 6 through which the end of the flattened portion of the leg extends as shown in the drawing. The leg is therefore, as will be understood, secured to the ring adjacent the inner end 70 of the horizontally extending flattened upper end thereof through the action of the slot 6 and offset at 4 and the extremity 5 of such portion. The upper ends of the legs thus having a horizontal portion extending beneath the horizontal portion of the ring and secured thereto adjacent the end of 80 such horizontal portion, it will be seen that after the leg and ring are in engagement movement of the leg outward from the axial line of the stand will swing the leg about its point of connection with the ring and force 85 the horizontal portion of the leg upward against the adjacent surface of the ring, thus securing an extremely rigid connection between the upper ends of the legs and the ring 2.

7 is a brace member connecting the legs of the stand together and which brace, as it is forced into place in assembling the stand, forces the legs outward and produces the interlocking action above explained. 95 This brace contacts, preferably, with the inner surfaces of the legs, as the legs may be more effectively forced apart if such is the case, and the brace after assuming a horizontal position is secured in place and 100 a more rigid structure procured by means of screws 8 which pass through washers 9 and engage cap nuts 10 the cap or head of which engages the outer surface of the legs.

In the modified form of my invention 105 shown in Figs. 4 and 5, the upper end of each of the legs is flattened and bent upon itself to form a loop at 12, the inner portion of which loop is in contact with the vertical portion of the ring 2 when the parts are assembled. The flattened portion of the leg is 110 bent a second time to form a horizontal ex-

tension 13 extending beneath the horizontal portion of the ring. The end of the horizontal extension 13 is preferably bent so as to extend upward over the inner edge and to 5 the upper surface of the horizontal portion of the ring as at 14, and the said horizontal portion of the flattened end of the leg is secured to the horizontal portion of the ring adjacent the inner edge thereof, either by 10 means of the upwardly bent end 14, or by means of a bolt 15 extending through the ring and leg, or by both said features. A recess 16 is also preferably provided in the ring 2 as shown and within which the bent 15 portion 14 aforesaid lies when the parts are assembled.

In the form of my invention shown in Figs. 4 and 5 in addition to the horizontal portion 13 being forced against the under 20 side of the ring as the parts are assembled the inner portion of the loop 12 is also forced against the vertical portion of the ring 2, whereby increased rigidity is secured.

In assembling the stand the legs are first 25 loosely engaged with the ring, after which the brace member is placed between the legs in an inclined position and then forced into a horizontal position, which act spreads the legs and forces the horizontal upper ends 30 thereof against the under side of the ring as explained.

In the modified form of my invention shown in Fig. 6 the upper ends of the legs are bent to form a loop at 17, the inner portion 35 of which is in contact with the vertical portion of the ring 2 when the parts are assembled, the same as in the form shown in Figs. 4 and 5. The legs have also horizontal extensions 18 beneath the horizontal portion 40 of the ring as in these figures but the legs are secured to the ring by causing their ends to extend through slots 19, similar to the method illustrated in Fig. 1, instead of by bending them upward over the inner edge 45 of the horizontal portion of the ring as in Figs. 4 and 5.

Having thus described my invention and explained the operation thereof, I claim and desire to secure by Letters Patent:

50 1. A water cooler stand comprising a ring adapted to support a water cooler and vertical sections of which are right-angular in form and the vertical portion of which ring is outermost; a plurality of legs the upper 55 ends of which are bent to provide a vertical portion in contact with the vertical portion of said ring and a horizontal portion in contact with and extending beneath the horizontal portion of said ring and inwardly toward the axial line of the stand, and the horizontal portion of each leg being secured adjacent its inner end to the horizontal por-

tion of said ring; and a brace member connecting said legs with one another, the arrangement of the parts being such that as 65 said brace member is placed in position the horizontal portions of said legs will be forced against the horizontal portion, and the vertical portions thereof against the vertical portion of said ring. 70

2. A water cooler stand comprising a ring adapted to support a water cooler and the lower surface of which ring lies in a horizontal plane and is of considerable extent in a radial direction, and said ring having a 75 plurality of oblong slots adjacent its inner periphery through which the ends of supporting legs may extend; a plurality of legs the upper ends of which are bent to provide a horizontal portion in contact with and extending beneath the lower surface of said ring and inwardly toward the axial line of the stand, and the horizontal portion of each leg being provided with an offset portion adapted to lie within the slots aforesaid 80 when the stand is assembled; and a brace member connecting said legs with one another, the arrangement of the parts being such that as said brace member is placed in position the horizontal portions of said legs 85 will be forced against the lower surface aforesaid of said ring.

3. A water cooler stand comprising a ring adapted to support a water cooler and vertical sections of which are right-angular in 90 form and the vertical portion of which ring is outermost, and the horizontal portion of said ring having a plurality of oblong slots adjacent its inner periphery through which the ends of supporting legs may extend; a plurality of legs the upper ends of which are bent to provide a vertical portion in contact with the vertical portion of said ring and a horizontal portion in contact with and extending beneath the horizontal portion of said ring and inwardly toward the axial line of the stand, and the horizontal portion of each leg being provided with an offset portion adapted to lie within the slots aforesaid 95 when the stand is assembled; and a brace member connecting said legs with one another, the arrangement of the parts being such that as said brace member is placed in position the horizontal portions of said legs 100 will be forced against the horizontal portion, and the vertical portions thereof against the vertical portion of said ring. 105

This specification signed and witnessed this twenty first day of July A. D. 1910.

HENRY G. CORDLEY.
